UNITED STATES PATENT OFFICE.

ARNO A. EWALD, OF OAKFIELD, WISCONSIN.

MUFFLER CUT-OUT.

1,183,361.

Specification of Letters Patent. Patented May 16, 1916.

Application filed January 21, 1915. Serial No. 3,541.

To all whom it may concern:

Be it known that I, ARNO A. EWALD, a citizen of the United States, residing at Oakfield, in the county of Fond du Lac and State of Wisconsin, have invented certain new and useful Improvements in Muffler Cut-Outs; and I do declare the following to be a full, clear, and exact description of the invention, such as will enable others skilled in the art to which it appertains to make and use the same.

My invention relates to improvements in muffler cut-outs and more particularly to those adapted for use on motor vehicles.

The main object of the invention is to provide a device of this character which may be stamped from a number of flat sheets of metal, preferably steel, thereby facilitating the manufacture of the device.

A further object of the invention is to so construct the cut-out as to allow exhaust gases to readily escape without passing through a number of couplings as is common with most forms of cut-outs now in use.

In carrying out this last named object, a further object is to provide a lever fulcrumed between its ends to swing in a plane transverse to the exhaust pipe, to curve one end of said lever to conform to the shape of the side of the exhaust pipe having the opening, and to widen this part of the lever, whereby it constitutes a valve plate.

Yet another object is to provide a single coil spring for returning a foot pedal, used in operating the cut-out, and the cut-out to normal position.

With the above and minor objects in view, the invention resides in certain novel features of construction and combination herein described and claimed and shown in the drawings wherein:—

Figure 1 is a top plan view of a portion of an automobile, showing the application of the invention thereto; Figs. 2 and 3 are vertical transverse sections as seen on the lines 2—2 and 3—3 of Fig. 1, the cut-out being shown respectively in open and closed positions; Figs. 4 and 5 are respectively top and bottom plan views of the cut-out and a portion of the exhaust pipe; Fig. 6 is a horizontal section taken on the plane of the line 6—6 of Fig. 3; Fig. 7 is a disassembled perspective view of a clamp to be described; and Fig. 8 is a similar view of the above mentioned lever.

In these drawings, constituting a part of

this application, a portion of an automobile A is shown which is equipped with an engine E, an exhaust pipe P which leads rearwardly from said engine beneath the floor 60 of the car, and with a muffler M which is located near the rear end of the pipe P. At a point interposed between the muffler M and the engine E, the pipe P is provided with a circular opening O. It is the purpose of the present invention, to open or close this opening at will. In accomplishing this result, the structure now to be described is employed.

Contacting with the lower side of the 70 pipe P, which side is equipped with the opening O, is a semi-circular clamping plate 1 which is provided with a central opening 2 registering with said opening O as clearly seen in Fig. 3. The upper edges of the 75 plate 1, are bent laterally to form attaching flanges 3 and 3', the intermediate portion of the latter being bent downwardly to provide pivot ears 4. Coacting with this clamping plate 1 is a second semi-circular 80 clamping plate 5 which embraces the upper half of the pipe P and whose lower edges are bent to provide laterally extending flanges which overlie the flanges 3 and 3', bolts 6 being then passed through these 85 flanges, whereby a complete clamp is provided, which is readily adaptable to most types of exhaust pipes.

Fulcrumed between its ends upon a pin 7 which passes through the two ears 4, is an 90 operating lever 8 which is preferably formed of steel so pressed as to provide a pair of depending pivot ears 9 which contact with the ears 4 and through which the pin 7 passes, one end of the lever rising 95 from the ears 9 while the other end thereof curves downwardly and laterally therefrom beneath the semi-circular plate 1. At this point, the lower end of the lever 8 is so curved as to conform to the shape of the plate 1 and is widened as seen at 10, to provide a valve plate for normally closing the opening therein, said plate being here shown as provided with an asbestos packing disk 11 on its upper side, whereby an air-tight 100 connection is formed between the valve plate and the plate 1.

From the free edge of the valve plate, the lever is curved downwardly to provide an attaching ear 12 to which one end of a 110 coil spring 13 is attached, said spring extending laterally inward from said ear and

having its opposite end connected to the lower end of the upright arm 14 of a bell crank lever 15, the latter being fulcrumed to a suitable bracket which is secured to the 5 floor of the machine, and having its horizontal arm pivoted to an upright link 16 whose upper end is equipped with a foot pedal 17. As most clearly seen in Figs. 2 and 3, the arm 14 of the bell crank lever is also connected to the opposite end of the lever 8, by a link 18, whereby depression of the horizontal arm by said lever will move the lever from the position seen in Fig. 3 to that seen in Fig. 2, whereupon the exhaust gases are 10 free to travel outwardly through the openings O and 2. This movement on the part of the bell crank and lever places the spring 13 under tension, which tension is then exerted to return the ports to normal position, 15 when so desired.

In most cases, it becomes expedient to provide means whereby the cut-out may be maintained in open position. For this purpose, one edge of the link 16 is provided 20 with a notch 19 which is engaged with a portion of the bracket through which it slides, as indicated in dotted lines in Fig. 2.

From the foregoing description, it will be seen that a very simple and efficient device 25 has been provided which may be easily and inexpensively manufactured of pressed steel or other suitable material, and that although a number of moving parts are employed, but one spring is necessary for returning all of 30 these parts to their normal positions. Furthermore, this one spring, designated by the numeral 13 in the drawings, also normally moves the arm 14 toward the upper end of the lever 8, thereby retaining the pivotal 35 connections of the link 18 with said arm and said lever, in tight contact, thereby preventing rattling of the various parts of the 40 device.

I claim:

45 1. The combination with an exhaust pipe having an opening, of a semi-circular clamp-

ing plate contacting throughout its width with said side of the pipe, said plate having an opening registering with that in the pipe, a clamping member passing around the 50 other side of the pipe and secured to said clamping plate, whereby a complete clamp is provided, a lever fulcrumed to said clamp to swing in a plane transverse to the pipe, and a valve plate carried by the lever, curved 55 to conform to the shape of the semi-circular clamping plate and normally closing the opening therein.

2. The combination with an exhaust pipe having an opening, of a semi-circular clamp- 60 ing plate contacting throughout its width with said side of the pipe, said plate having an opening registering with that in the pipe, a clamping member passing around the other side of the pipe and secured to said clamp- 65 ing plate, whereby a complete clamp is pro- 65 vided, a lever fulcrumed between its ends to said clamp to swing in a plane transverse to the pipe, the portion of said lever to one side of its fulcrum being widened and 70 curved to conform to the shape of the semi- 70 circular clamping plate, whereby to consti- 75 tute a valve for closing the opening therein, and means connected with the other end of the lever for rocking the same around its 75 pivot to move said plate to inactive position.

3. In combination, a muffler cut-out in- 80 cluding a lever fulcrumed between its ends, an operating lever spaced laterally from the cut-out and having an end movable away therefrom, a link connecting said end of the operating lever with one end of the lever on the cut-out, and a coil spring connecting the other end of said lever on the cut-out with the aforesaid end of the operating lever. 85

In testimony whereof I have hereunto set my hand in presence of two subscribing wit- 80 nesses.

ARNO A. EWALD.
